(57) **CLAIM**

The ornamental design for an oral-motor chew tool, substantially as shown and described.

DESCRIPTION

FIG. 1 is a top, front, right perspective view of an oral-motor chew tool, showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in FIG. 3 depict a portion of the oral-motor chew tool that forms no part of the claimed design.

1 Claim, 5 Drawing Sheets(56)
